CLAIM

The ornamental design for a power supply for a wireless car phone, as shown and described.

DESCRIPTION

FIG. 1 is a perspective view of a power supply for a wireless car phone;

FIG. 2 is a top view thereof;

FIG. 3 is a bottom view thereof;

FIG. 4 is a right side elevated view thereof;

FIG. 5 is a left side elevated view thereof;

FIG. 6 is a front view thereof; and,

FIG. 7 is a rear view.

In FIG. 1, the broken lines indicate a continuous coiled cord and the cord is shown broken away to indicate indeterminate length. In FIGS. 2-7, the coiled portion of the cord along with the attached connector are omitted for convenience of illustration.
